UNITED STATES PATENT OFFICE

GUSTAF C. F. BECK, OF MINNEAPOLIS, MINNESOTA, ASSIGNOR OF FORTY-NINE ONE-HUNDREDTHS TO GEORGE O. DARROW, OF MISSION SAN JOSE, CALIFORNIA

PLIERS

Application filed April 3, 1931. Serial No. 527,372.

This invention relates to pliers and more particularly to pliers mainly utilized for the purpose of gripping and turning nuts, pipes, etc.

5 At the present time slip joint pliers are widely used to afford a desired degree of adjustability for gripping nuts and pipes varying considerably in size.

The pivotal connection between the two 10 crossed members may be shifted when the members are disposed in a predetermined, widely swung position. This shifting requires time and furthermore, the pivot pin which is flattened will often become worn after 15 hard use, with the result that the crossed members will accidentally slip from the first to the second or wider adjusted position.

It is an object of my invention to provide 20 exceedingly simple, but highly efficient pliers wherein comparatively wide adjustment in the spaced relations of the jaws may be obtained without manually shifting the position of the pivot point and wherein the strains are received and distributed upon the 25 pivotal portions in an efficient manner.

More specifically it is an object to provide 30 gripping pliers wherein a pair of crossed members are connected together by means of a special cam bearing permitting free pivoting of the members while automatically shifting the axis of the pivotal connection as required in accordance with the size of the article to be gripped.

It is a further object of my invention to 35 provide a pair of gripping pliers wherein the cooperating jaws are provided with cooperating means for tightly engaging the oppositely disposed corners of nuts and wherein further provision is made for gripping pipes and also relatively small articles.

Still another object is to provide in pliers 40 of the class described means for limiting the opening member of the tool to a position where the shanks or handles of the members may be surrounded with the normal extended grip of the hand.

These and other objects and advantages of 45 the invention will be fully set forth in the 50 following description made in connection

with the accompanying drawing, in which like reference characters refer to similar parts throughout the several views, and in which:—

Fig. 1 is a plan view of an embodiment of 55 my invention with the pliers in an intermediate open position, a portion of the disk or retaining flange of the pivot member being broken away to show the shape and construction of the camming surfaces;

Fig. 2 is a cross section taken on the line 2—2 of Fig. 1;

Fig. 3 is a side elevation of the complete cam pivot detached, and

Fig. 4 is a plan view of a slightly different 65 form of the invention with the members shown in closed position.

As shown in the drawing, my pliers comprise a pair of crossed members designated as entireties by the numerals 5 and 6 and having the cooperating jaw portions 5a and 6a respectively and the shanks or handle portions 5b and 6b. Said members may be constructed from cast iron, case hardened metal or tool steel or any suitable material. The 70 members on their opposing surfaces are provided with flat bearing portions and member 5 is provided with a cam pivot 7 which projects normal its bearing portion and which is of figure 8 shape in cross section. Cam 75 pivot 7 has a reduced shank 7a which may be flattened to non-rotatively engage a complementary shaped aperture formed through the cross portion of member 5 and a retaining nut 8 may be threadedly secured to the 80 projecting end of said shank. The longitudinal center line of the cross sectional area of cam pivot 7 extends at an acute angle to the longitudinal center line of the pair of pliers when the same are in closed position. 85 In the form shown I find that the said angle may effectively be between 30 degrees and 50 degrees, although of course further variation may be made, all within the scope of my invention.

The bearing portion of member 6 is provided with a centrally disposed aperture in the shape of a figure 8 forming a peripheral bearing or camming edge E for engagement with the cam pivot 7. It will be noted 90 that the cam pivot 7 is disposed in the center of the bearing portion of member 6. The 95 peripheral bearing edge E is disposed in the center of the bearing portion of member 6. The 100 peripheral bearing edge E is disposed in the center of the bearing portion of member 6.

that the figure 8 shaped camming edge is of approximately the same length as the cross sectional length of cam pivot 7 but is considerably wider and is not symmetrically shaped. The corners of the figure 8 edge are spaced apart and properly shaped to closely engage slippage portions of the cam pivot when the pliers are in closed position and when the pliers are in fully opened position. The longitudinal center line of the bearing or camming edge E substantially coincides with the longitudinal center line of the pliers when the same are in closed position.

15 The cam pivot 7 carries an external disk or flange 7b which is adapted to slightly overlap and cover the bearing edge E defined in the aperture in member 6 and retaining the two parts of the pliers together in operative relation.

20 The cooperating surfaces of the jaws shown in Fig. 1 are provided with angular oppositely disposed recessed portions R which are adapted to receive and tightly grip oppositely disposed corners of a hexagonal or octagonal nut. Member 5 has a toothed pipe-gripping portion 5c on the jaw disposed inwardly or toward the pivot from the angular gripping portion R and member 6 has a cooperating angled portion 6c disposed oppositely thereto.

25 The form of the invention shown in Fig. 4 is similar to the form previously described with the exception that the jaws thereof are provided with the conventional pipe-gripping teeth rather than the special cooperating gripping elements shown in Fig. 1.

30 In use the pliers will be manipulated in the conventional manner the members being swung together by movement of the handle portions or shanks. The relative positions of cam pivot 7 and bearing edge E will automatically be determined by the thickness or size of the nut, pipe or other article gripped by the jaws. In other words, there will be an automatic lateral shifting of the member 6 relatively to the cam pivot 7 when the same is necessary to extend the jaws or widen the space between the cooperating edges thereof.

35 In every instance pressure will be applied between portions of the cam edge of member 7 and the bearing edge E of member 6 and in most instances the strain will be distributed between two oppositely disposed points on the pivot and on the bearing edge. The thrust will always be a downward or inward thrust with reference to the outer portions of the pliers which engage the object to be gripped.

40 With my structure I am able to obtain a greater or at least as great a range of adjustability of the jaws with the same spread of the handle members or shanks as in the conventional slip joint pliers extensively utilized. This adjustment as has been shown

is automatically effected, the slippage of the camming and pivotal elements occurring without setting on the part of the user.

45 It will be noted that due to the type of pivotal connection, strains and stresses will be distributed and the inter-connections of the two members will be relatively strong without increasing the dimensions above the conventional size.

50 It will also be noticed that the heaviest strains are applied in a direction longitudinal of member 6 and the narrower portions surrounding the bearing edge E will therefore not break with hard usage.

55 From the foregoing description it will be seen that I have invented a very simple, practical and highly efficient pair of pliers capable of wide general use and adapted to be manufactured as cheaply as conventional slip joint pliers now extensively utilized.

60 It will, of course, be understood that various changes may be made in the form, details, proportions and arrangement of the parts, without departing from the scope of my invention, which, generally stated, consists in a device capable of carrying out the objects above set forth, and in the novel parts and combinations of parts disclosed and defined in the appended claims.

65 What is claimed is:—

1. In pliers, a pair of swingably united crossed members having cooperating jaw portions, one of said members carrying at its crossed portion a substantially elliptical upstanding cam pivot, the other of said members having a substantially elliptical apertured portion provided with a bearing edge, said apertured portion being substantially equal in its longer dimension to the longer dimension of the cross section of said cam pivot but substantially greater in its shorter dimension than the shorter dimension of said cross section and means associated with said cam pivot for retaining said members together for swinging movement.

2. In pliers, a pair of elongated crossed members having cooperating jaw portions, one of said members carrying at its crossed portion an upstanding cam pivot of general elliptical cross sectional shape, the center line of which is disposed at an acute angle to the longitudinal center line of the pliers when said members are swung together, the second of said members having an apertured portion provided with a bearing edge, the longer dimension of said apertured portion being of substantially the length of the longer dimension of the cross section of said cam pivot, but the shorter dimension being substantially greater than the shorter dimension of the cross section and means for retaining said members together for swinging movement.

3. In pliers, a pair of crossed members having cooperating jaw portions, one of said

members carrying at its crossed portion an upstanding cam pivot of figure 8 shape in cross section, the other of said members having a figure 8 shaped aperture there-
5 through, leaving a bearing edge adapted to cooperate with said cam pivot, the longer dimension of said aperture being substantially equal to the longer dimension of the cross sectional area of said cam pivot but the
10 shorter dimension being substantially greater than the shorter dimension of said cross sectional area and the diagonal corners of said apertured portion being spaced apart a distance substantially equal to the longer dimension of the cross section of said cam pivot,
15 the outer end of said cam pivot carrying means for connecting said members together for swinging movement.

4. In pliers, a pair of crossed members having cooperating jaw portions, one of said members carrying at its crossed portion an upstanding cam pivot of figure 8 shape in cross section, the other of said members having a recessed portion provided with a bearing edge adapted to cooperate with said cam pivot, said bearing edge being also of figure 8 shape and having a longer dimension substantially equal to the longer dimension of the cross sectional area of said
25 pivot but having a shorter dimension substantially greater than the shorter dimension of said cross sectional area, the longitudinal cross sectional line of said pivot extending at an acute angle to the longitudinal center line
30 of the pliers when said members are swung to closed position and said bearing edge extending longitudinally of said center line of the pliers when the members are in closed position.
35

40 In testimony whereof I affix my signature.
